RADIATOR FOR GLUING MACHINES

Filed Nov. 1, 1947

4 Sheets-Sheet 4

Boards O having their edges glue-coated are forced into and through the heating chamber D by forcing means P and the adjacent boards within the chamber are held in substantially uniform abutting contact by retarding means Q which yieldingly resists movement of the boards from the chamber by the forcing means.

With this construction, the upper radiator may be elevated relatively to the lower radiator to receive boards of different thicknesses, and the upper radiator may be pulled downwardly to press the boards between the radiators.

Each radiator comprises side and end pieces 1 and 2 and intermediate cross pieces 3 preferably formed of metal channels, all of said pieces being connected together into a frame as by flexible angle pieces 4 welded at the joints between the respective side, end and cross pieces. Secured to the bottom flanges of the side pieces, end pieces and cross pieces of the upper radiator in any suitable manner is a platen comprising a plurality of flexible steam pipes 5 that are nested between flexible metal T-bars 6 which extend lengthwise of the radiator. Preferably, the pipes and T-bars are welded to each other and to the frame pieces 1, 2 and 3, and the heads or cross portions of the T-bars are disposed in the same horizontal plane to form a smooth heating or board-engaging surface 7. The pipes are preferably connected at their ends to manifolds 5a which may be connected to any suitable source of heating or cooling fluid.

The lower radiator is similarly formed, having side, end and cross pieces 8, 9 and 10, respectively, but the steam pipes 11 and T-bars 12 are arranged on the upper flanges of the radiator in opposed relation to the pipes 5 and T-bars 6 of the upper radiator to form a board-engaging surface 13.

In accordance with the invention, the upper radiator is adjustable so as to compensate for warping of the heating surface 7 thereof and to ensure that said surface shall be absolutely flat or planar. As shown, the side, end and cross pieces of the radiator are slit for portions of their widths from the top flanges to points closely adjacent the lower flanges, as indicated at 14, and an adjusting screw 15 extends transversely of the open end of each slit and has its ends slidable through blocks 16 which are secured to the upper flanges of the respective frame pieces in any suitable manner, as by welding. Nuts 17 are screwed onto the ends of the screws 15 at opposite sides of the respective blocks 16 for adjusting the screws and for locking them in adjusted positions.

With this construction, it will be observed that by proper manipulation of the screws, the frame pieces, T-bars and pipes may be flexed as required to make the heating or board-engaging surface 7 of the radiator truly flat. It will be observed that each heating pipe is nested between the main and cross flanges of two adjacent T-bars so as to be protected against the pressure applied to the board-engaging surfaces of the radiators. Moreover, the pipes are in direct heat-transmitting contact with the T-bars so that heat is efficiently conducted to the board-engaging surfaces 7 and 13. Furthermore, the construction contributes substantially to the flexibility of the upper radiators and makes the board-engaging surface easily conformable to the surfaces of the boards.

Instead of using T-bars, it will appear to those skilled in the art that ordinary angle bars could

be substituted for the T-bars, each angle bar having one flange secured to the frame of the heating plate and its other flange disposed in substantially a common flat plane with the flanges of the other bars.

Furthermore, while we have described the pipes for steam, obviously other suitable heating or cooling elements might be utilized and hot or cold oil or other fluids could be circulated through the pipes instead of steam. From the foregoing, it will be observed that the platens embodying the invention could be used for cooling or refrigerating purposes as well as heating purposes.

While we have shown and described the now preferred embodiment of our invention, it should be understood that this is primarily for the purpose of illustrating the principles of the invention and that the structure of the radiator or platen may be widely modified and changed within the spirit and scope of the invention.

Having thus described the invention, what we claim is:

1. A platen having a flat planar object-engaging surface for pressing flat objects between it and another flat surface, said device comprising a rectangular open frame having one side in substantially a flat plane, a plurality of separate parallel bars secured to said side of said frame and having surfaces in substantially a common flat plane to form said object-engaging surface, said frame and bars being flexible to dispose said object-engaging surface in flat condition, and means for positively flexing said frame and bars to adjust said object-engaging surface and for holding them in adjusted position.

2. A platen having a flat planar object-engaging surface for pressing flat objects between it and another flat surface, said platen comprising a frame, surface-forming means thereon having said object-engaging surface, means for flexing said frame and said surface-forming means to maintain said surface in flat unwarped condition and thus ensure substantially uniform pressure upon objects between said object-engaging surfaces and flexible heating pipes mounted on said frame in heat-conducting contact with said surface-forming means for heating said surface.

3. A platen having a flat planar object-engaging surface for pressing flat objects between it and another flat surface, said platen comprising a rectangular open frame having one side in substantially a flat plane, a plurality of separate parallel bars secured to said side of said frame and having surfaces in substantially a common flat plane to form said object-engaging surface, said frame and bars being flexible to dispose said object-engaging surface in flat condition, said bars being T-shaped in cross-section and having their main flanges secured to said side of said frame with their cross flanges disposed in said common substantially flat plane, and flexible heating pipes one of which lies between the main flanges of each two adjacent bars.

4. A platen having a flat planar object-engaging surface for pressing flat objects between it and another flat surface, said platen comprising a rectangular open frame having one side in substantially a flat plane, a plurality of separate parallel bars secured to said side of said frame and having surfaces in substantially a common flat plane to form said object-engaging surface, said frame and bars being flexible to dispose said object-engaging surface in flat condition, said frame being rectangular and formed of side

pieces, end pieces and cross pieces secured together by flexible joints.

5. A platen having a flat planar object-engaging surface for pressing flat objects between it and another flat surface, said platen comprising a rectangular open frame having one side in substantially a flat plane, a plurality of separate parallel bars secured to said side of said frame and having surfaces in substantially a common flat plane to form said object-engaging surface, said frame and bars being flexible to dispose said object-engaging surface in flat condition, said frame being rectangular and formed of side pieces and end pieces and cross pieces having their opposite ends abutting the respective side pieces, and angle pieces flexibly fastening said ends of said end pieces and cross pieces to said side pieces.

6. A platen having a flat planar object-engaging surface for pressing flat objects between it and another flat surface, said platen comprising a frame, surface-forming means thereon having said object-engaging surface, means for flexing said frame and said surface-forming means to maintain said surface in flat unwarped condition and thus ensure substantially uniform pressure upon objects between said object-engaging surfaces, said frame being formed of pieces having flanges extending at one edge in a plane parallel to the plane of said object-engaging surface and said pieces are formed with slits extending from the opposite edges to points adjacent said flanges of the respective pieces, and means adjustably connecting the portions of said pieces at opposite sides of each slit for flexing said frame.

7. A platen having a flat planar object-engaging surface for pressing flat objects between it and another flat surface, said platen comprising a frame, surface-forming means thereon having

said object-engaging surface, means for flexing said frame and said surface-forming means to maintain said surface in flat unwarped condition and thus ensure substantially uniform pressure upon objects between said object-engaging surfaces, said frame being formed of pieces having flanges extending at one edge in a plane parallel to the plane of said object-engaging surface and said pieces are formed with slits extending from the opposite edges to points adjacent said flanges of the respective pieces, a block secured at each side of each slit to the corresponding frame piece, and a bolt adjustably connecting said blocks for each slit to permit the corresponding frame piece to be bent at the juncture of said slit and said flange of the corresponding frame piece.
